UNITED STATES PATENT OFFICE

JOHN MACGREGOR, OF WHEATON, ILLINOIS

GOLF-COURSE BRUSH

Application filed December 20, 1924. Serial No. 757,144.

This invention relates to apparatus for treating and caring for lawns, greens of golf courses, and the like, and has for a primary object the provision of a machine adapted to form a part of the equipment of a golf course for spreading compost on the greens after the same has been deposited.

An important object of the invention is the provision of a light weight machine adapted to be operated rapidly and efficiently to scatter the compost evenly and uniformly over the green with the least possible effort and minimum requirement for attendants to do the work.

Another and highly important feature of the invention is the provision of a compost spreading machine which may be economically manufactured and which, while strong and durable in service, requires a relatively small number of parts and manufacturing operations.

A highly desirable feature of the invention is the arrangement of the brush in firmly supported relation behind the wheels of the machine, so that the desired pressure thereon may be easily exerted by downward pressure upon the pushing handle, by means of which the machine is propelled over the green.

Another important object of the invention is to provide a simple and efficient device for destroying the parasitic fungi.

Other objects and advantages of the invention will be apparent as it is better understood from the following description, which, taken in connection with the accompanying drawings, discloses a preferred embodiment thereof.

Referring to the drawings,

Figure 1 is a top plan view of a compost spreader in which my invention is embodied;

Figs. 2 and 3 are, respectively, end and side elevations thereof; and

Fig. 4 is an enlarged perspective view of

the means for attaching the supporting braces to the brush bar.

In said drawings, I have shown, for illustrative purposes only, a preferred embodiment of my invention, in which the reference character 21 indicates an axle, upon the ends of which wheels 22 are mounted, in any suitable manner, these wheels being, if desired, ordinary iron wheels and having sufficiently wide treads to prevent cutting of the greens. Brace bars 23 extend rearwardly from the axle 21, inwardly from the wheels, and the ends 24 thereof are attached by means of bolts 25 to a push bar 26, having a spindle 27 attached to the rear end thereof and extending to opposite sides, so that the machine may be handled by a single attendant.

A brush bar 28 that is preferably of sufficient length to extend a substantial distance beyond the wheel tracks or the gauge of the wheels on each side is supported from the bar 26 and the braces 23 by means of brace rods 29 and 31, the rods 31 being secured at 35 to the rearwardly extending brace bars 23 and the rods 29 being secured by means of bolts 36 to the ends 24 of said bars and to the push bar 26, the lower ends of said bars being turned and flattened, as indicated at 37 and 38, and secured by bolts 39 to channel-shaped brackets 41, fitting upon the brush bar 28 in which bristles 42 are clamped in any suitable manner, bolts 43 being provided to hold said brackets 41 in place.

The angularity of said rods 29 and 31 may be varied by loosening the nuts on the bolts 35 and 36 and the vertical position of the brush thus adjusted.

After the compost has been deposited upon the greens, it is not uniformly distributed, even though the best type of distributing machine be used, and the attendant may follow the distributing operation with the use of my spreading machine, bearing down upon

the brush with any desired degree of pressure so that any irregularities or piles of compost may be removed and the surface of the greens rendered smooth and even, with the compost distributed in such manner as to obtain the best results for fertilizing purposes and not interfering in any manner with the use of the greens.

By the use of my machine, the compost is not only evenly distributed, but is rubbed into the soil and the grass is evened up and left standing in normal condition as it was before the work began. This is a very distinct improvement over the method which has heretofore generally been used for the purpose and which has involved the use of a drag, which leaves the grass mashed down and parts thereof often covered with the compost, so that it will turn yellow and perhaps be killed. In order to obtain satisfactory results with this method, it has been found necessary to follow the drag with the use of a hand rake, whereas when the machine of my invention is used, this extra work is avoided and much more efficient results obtained by going over the green a single time.

The machine or device is also capable of use as a destroyer of parasitic fungi, aside from its above mentioned use, or in combination therewith, this being accomplished by operating the machine over the greens of a golf course or other vegetation to be treated, before sunrise or immediately thereafter, which permits the grass or vegetation to dry more rapidly and before the atmospheric temperature is high enough to permit propagation of the fungi, and since the fungi do not propagate on dry vegetation they are destroyed.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. A light weight machine for working compost into golf course greens and the like, comprising narrow-faced wheels, a rigid handle extending rearwardly therefrom for directing the same, and a brush disposed rearwardly of the wheels rigidly secured to said handle and adapted for manipulation by said handle to produce the desired pressure thereon.

2. A machine for working compost into golf course greens and the like, comprising wheels, an axle upon which said wheels are mounted, a push bar for directing said wheels, frame parts extending rearwardly from the axle and secured to said bar, a

brush disposed rearwardly of the wheels, brace rods extending rearwardly from said frame part parallel with the inner face of the wheels and secured to said brush, brace rods extending diagonally from the push bar to the points of attachment of the first-mentioned rods, and means for securing both said parallel and diagonal rods to the brush.

3. A machine for treating golf course greens and the like, comprising a pair of spaced narrow-faced wheels, an axle upon which said wheels are mounted, a rigid handle having bearings on said axle adjacent each wheel for directing the same, a brush rigidly attached to said handle and arranged parallel with said axle, said brush being of greater length than the axle so as to treat an area of greater width than the tracks of said wheels, the whole machine being of relatively light weight.

4. A machine for treating golf course greens and the like, comprising, a plurality of narrow faced wheels, an axle arranged for supporting said wheels in spaced relation, a rigid operating handle arranged to engage the axle at points located adjacent each wheel and having portions extending parallel with a side of each wheel, a brush arranged parallel with the axle and adjacent the wheels, and means for rigidly securing said brush to said rigid operating handle, said means comprising rods connected to said brush adjacent the opposite ends thereof and connected to the portion of the handle that extends parallel with the side of a wheel and rods connected with the brush adjacent the ends thereof that are arranged diagonally to a point on the handle located near the longitudinal center of the machine.

5. A machine for working compost into golf greens and the like, comprising wheels, an axle upon which said wheels are mounted, a push bar, yoke members attached to said push bar and said axle, a brush, and means connecting said brush to said yoke members adjacent the axle and adjacent the connection of said yoke members with said push bar.

6. A machine for working compost into golf greens and the like, comprising wheels, an axle upon which said wheels are mounted, a push bar and brace member at each side of said push bar and having an end bent to extend alongside the lower end of the push bar, and an end bent into substantial parallelism therewith for engagement with the axle, the body of said braces extending generally out from the push bar to adjacent the ends of the axle, a brush arranged behind the axle and wheels and beneath the push bar, and a brace extending rearwardly and downwardly from adjacent the lower end of the push bar and to said brush, all said braces being secured to said push bar.

7. A machine for working compost into

golf greens and the like, comprising wheels, an axle upon which said wheels are mounted, a push bar and brace member at each side of said push bar and having an end bent to extend alongside the lower end of the push bar, and an end bent into substantial parallelism therewith for engagement with the axle, the body of said braces extending generally out from the push bar to adjacent the ends of the axle, a brush arranged behind the axle and wheels and beneath the push bar, and a brace extending downwardly from adjacent the lower end of the push bar and to said brush, all said braces being secured to said push bar.

JOHN MacGREGOR.
